UNITED STATES PATENT OFFICE.

WILLIAM D. KELLY, OF JEFFERSON, TEXAS.

SPIKE-HOLDER.

1,143,051.

Specification of Letters Patent. Patented June 15, 1915.

Application filed October 15, 1914. Serial No. 866,840.

To all whom it may concern:

Be it known that I, WILLIAM D. KELLY, a citizen of the United States, residing at Jefferson, in the county of Marion and State 5 of Texas, have invented a new and useful Spike-Holder, of which the following is a specification.

The present invention relates to improvements in spike holders, one object of the 10 present invention, being the provision of means adapted to encircle the body portion of a railroad spike, one upon each side of the rail to hold the spikes against spreading relative to each other, such device being further provided with means for entering or 15 engaging the tie to prevent transverse movement thereof.

A further object of the present invention, 20 is the provision of a spike holder made from a single strand of wire and bent to provide two spike receiving eyes or loops and two tie engaging prongs, there being further provided two coils about the body of the wire to engage the base of the rail and thus prevent 25 the body of the wire therebelow from being abraded and broken.

A still further object of the present invention is the provision of a simple, durable and inexpensive device of this character which is 30 readily applied when the spikes are being driven to hold the rail in position upon the tie.

With the foregoing and other objects in view which will appear as the description 35 proceeds, the invention resides in the combination and arrangement of parts and in the details of construction hereinafter described and claimed, it being understood that changes in the precise embodiment of 40 the invention herein disclosed can be made within the scope of what is claimed without departing from the spirit of the invention.

In the drawings—Figure 1 is a top plan view of one form of spike holder embodying the present invention. Fig. 2 is a side view thereof. Fig. 3 is a cross section through a rail and the adjacent portion of the tie showing the present spike holder in operable relation. Fig. 4 is a top plan view of 45 another construction of spike holder embodying the present invention. Fig. 5 is a side view thereof. Fig. 6 is a top plan view of still another form of spike holder embodying the present invention. Fig. 7 is a side elevation thereof.

Referring to the drawings, the numeral 1

designates the straight connecting portion of the holder which is provided at the opposite ends thereof with the oppositely disposed spike receiving loops 2 and with the 60 coiled portions 3 which surround the body portion of the holder, the coil at the eye portion passing below the body portion and terminating in the tie engaging or entering prong 4.

As shown in Fig. 3, the body portion of the holder is disposed below the base 5 of the rail 6 so that the coils 3 engage the base of the rail and thus prevent the abrasive action upon the body of the holder. The 70 spikes 7 are so driven as to be presented through the loops of the present holder while the tie entering portions of the holder are driven into the tie 8 and are thus held more securely in place by the weight of the 75 rail thereupon.

It will thus be seen that the present holder will properly encircle the spikes and hold them against outward displacement or any movement relatively to each other and thus 80 to a great extent, the head of the inner spike will assist the head of the outer spike, or vice versa, where the lateral strain upon the rail is such as to tend to shear the head.

In the construction of tie holder shown 85 in Figs. 4 and 5, the body portion 1' is employed and the loops 2' are bent so that the coils 3' thereof are started from above terminating in the tie engaging prongs or pins 4'. In this instance, the loop portions are 90 offset or extend in opposite directions as illustrated in Figs. 1 and 2.

In the construction shown in Figs. 6 and 7, the body portion 1^a is provided with the loops 2^a at the opposite ends, the center of 95 said loops being alined with the body portion and said loops not being offset as shown in Figs. 1 and 4. In this instance, the coil 3^a is disposed at one side of and centrally of each respective loop around the body portion 1^a, while the terminal or prong 4^a is formed to enter the tie as in the other holders.

What is claimed is:

1. A spike holder made from a single 105 strand of wire and bent to provide two spike receiving loops, one at each end thereof, and a tie entering prong to each loop.
2. A spike holder made from a single 110 strand of wire and bent to provide two spike receiving loops, one at each end thereof, a tie entering prong to each loop, and two

coils one adjacent each loop disposed upon the body of the strand of wire for interpolation upon the tie and against the base of the rail to hold the base of the rail from engagement with the intervening portion of the strand of wire.

3. A spike holder made from a single strand of wire, and having each terminal thereof bent to form a loop, terminating in a coil upon the body of the strand of wire.

4. A spike holder made from a single strand of wire, and having each terminal

thereof bent to form a loop, terminating in a coil upon the body of the strand of wire, the extreme end of such coil being 15 bent downwardly and sharpened to constitute a tie entering prong.

In testimony that I claim the foregoing as my own, I have hereto affixed my signature in the presence of two witnesses.

W. D. KELLY.
